UNITED STATES PATENT OFFICE.

JOSEPH KAHN, OF CHICAGO, ILLINOIS.

LOOSE-LEAF BINDER.

Application filed January 31, 1924. Serial No. 689,634.

To all whom it may concern:

Be it known that I, JOSEPH KAHN, a citizen of the United States, and a resident of Chicago, in the county of Cook and State 5 of Illinois, have invented certain new and useful Improvements in Loose-Leaf Binders, of which the following is specification.

This invention relates to improvements in loose leaf binders and more particularly to 10 an improvement in the form of binder disclosed in a prior application filed by me on September 22, 1923, and bearing Serial No. 664,154.

The object of the present invention is to 15 provide a construction for a binder, more particularly to the parts constituting the contents securing means, whereby the particular method or principle involved may be available for more extensive usage and 20 adaptation in the art, by simplifying and improving the structure to such an extent as to permit the locking device to be readily incorporated in loose leaf note books, record books and the like.

25 A preferred embodiment of the invention is disclosed in the accompanying drawings in which—

Figure 1 is a fragmentary view in perspective of a binder equipped with the improved locking devices;

30 Figure 2 is a fragmentary view of a book in fully open position showing one of the locking devices in detail with the parts thereof in locking position;

35 Figure 3 is a view similar to Figure 2, with the parts shown in section, to disclose the construction more clearly;

40 Figure 4 is a detailed view of the locking mechanism shown in Figure 3 with the parts shifted into an unlocking position;

45 Figure 5 is a detailed view slightly enlarged and showing the locking parts in unlocking position as viewed from the side and preparatory to inserting the sheet or sheets into the binder;

Figure 6 is a view corresponding to Figure 5 with the parts shown in longitudinal section;

50 Figure 7 is a view corresponding to Figure 5 with the parts shifted into locking position;

Figure 8 is a view similar to Figure 6, but corresponding to Figure 7 in that the parts are shown in locking position;

55 Figure 9 is a perspective view of a portion of the locking member with the parts

assembled to show more clearly the construction, and

Figure 10 is an enlarged detailed view 60 in cross section of the binder in closed position as taken on line 10—10 of Figure 2.

The binder comprises in general,—a binder cover consisting of top and bottom cover members 1 and 2 respectively, connected or hinged to a back section 3, and containing 65 the binder contents 4 of the sheets or leaves removably held within the binder cover by means of the improved contents securing members consisting primarily of binder posts 5 extending transversely of the binder 70 when in closed position immediately adjacent the back section 3. Without going into detail at this time as to the manner in which the posts are mounted, it may be observed that the same are hinged at their lower ends 75

to the intermediate member 6, extending longitudinally of the binder at the junction or line of hinged connection between the bottom cover 2 and the back section 3, and detachably connected and hinged at their 80 upper or free ends to a somewhat similar intermediate attaching or locking member 7 extending longitudinally of the binder and along the line of hinging between the top cover section 1 and said back section 3. The posts 5 are preferably curved or rounded 85 throughout their central portions and in a direction away from the back section so as to give them a somewhat curved formation not unlike the similar elements found 90 in the binders of the so-called ring type.

The binder cover may be either of the stiff or flexible form, that is to say, the covers and back sections may be of limp leather such as 95 ordinarily used in loose leaf memorandum books for pocket use, or they may be of a stiff construction such as is found in record and account books for office use. It is to be particularly noted that in the binder disclosed, the covers are hinged directly to

100 the back section so that the binder opens and is otherwise constructed in the same manner as in an ordinarily bound volume. This is pointed out in order to draw distinction between the classes of lightly constructed binders and the more ponderous and massively constructed binders wherein the covers are hinged, forwardly of the back section with an inflexible rail in between.

105 Proceeding now with the description of the contents securing parts, the member

heretofore referred to as intermediate connecting member 6, consists of a tubular rail 8 extending substantially the full length of the binder and preferably constructed of thin sheet metal shaped in tubular form, with a radially extending flange 9, which lies flatwise against the bottom cover and is riveted or otherwise secured permanently thereto, the major portion of the flange 9 being covered or concealed beneath the finishing layer or covering 2^a extending over the inside surface or bottom cover 2. At points spaced inwardly from the ends of the tubular rail 8 and at a point midway therebetween, are formed notches or openings 10 facing in a general upwardly direction to receive the lower ends of the post 5. As clearly shown in Figures 1 and 3 the end portions of the posts are straight and provided at their extremities with transverse openings 5^a whereby they are joined in hinged connection with the members 3 and 7. Extending lengthwise of the tubular rail 8 is a rod 11 passing through the openings in the lower end of the post 5 and secured against displacement in any suitable manner at the ends of the tubular rail 8. In this manner the posts are free to turn on the rod 11, the openings 10 being sufficiently large in their circumferential dimension to permit the free movement of the posts.

Referring now to the locking mechanism, the same consists of parts constituting the member 7 extending longitudinally of the binder at the junction of the top cover 1, and the back section 3. The member 7 comprises tubular rails 12, formed integral with a flange 13, extending flatwise along the cover a short distance inwardly from the hinged edge.

The tubular rails 12, are located at the ends and central portions of the flange 13, and extend a short distance in both directions from the points at which the posts 5 are attached, these points being identified by notches or recesses 14, located intermediate the ends of each rail 12, and formed by removing sections of the rails as shown in Figure 9. It may be observed that the rails 12 can be united in a single tubular rail extending the full length of the member 7, but for reasons hereinafter pointed out the sectional rail is preferable.

Mounted on the tubular rails 12, and slideable endwise thereon is a sleeve 15, slightly longer than the distance between the end of the tubular rails, this difference determining the extent of the sliding movement of the sleeve. At the ends of the sleeve are inserted heads 16, for convenience in shifting the sleeve in opposite directions. The amount that the sleeve may be shifted is determined by movement required to complete the locking and releasing of the posts,

which is approximately the same as the width of the notches 14. Formed in the sleeve 15 are notches or recesses 17 corresponding to the notches 14 in the tubular rails and are of the same width and circumferential dimensions. At one side of each notch 17 is a smaller notch or recess 18, opening laterally into the larger notch. These smaller notches are of a size to receive the ends of the posts and the entrance thereto is of sufficient width to allow the posts to pass from one notch to the other in the movement of the sleeve. The location of the smaller notches 18, with respect to the circumference of the sleeve is clearly indicated in Figure 1, namely, facing toward the posts when the top cover is turned back to the position shown in Figure 1, or better, when the cover 1 stands at right angles to the bottom cover. In other words, it is intended that the binder shall be opened to a definite position to make the locking action possible. This will be explained later in more detail.

In order to provide increased bearing for the sleeve, short marginal flanges 15^a 15^b are formed along the two edges of the sleeve which embrace the flange 13 secured to the binder cover, it being obvious that a space or slot must be provided along the rear side of the sleeve to permit the flange 13 to join the tubular rails enclosed within the sleeve.

The addition of locking members completes the device, these having the form of locking pins 19 located within the sleeve 100 and are fixed thereto. As clearly shown in Figure 9 each locking pin, comprises a cylindric base portion 19^a which fits snugly in the sleeve, just beyond the end of the tubular rail 12, associated therewith and is secured by a rivet or pin 20 extending through said base. The locking pin 19 extends from the base 19^a and engages the passage formed by the tubular rail. In one position, Figure 8, the pin traverses the recess 12 and forces through the eye in the post 5, and in the unlocking position it is withdrawn from the recess and from said eye, Figure 6.

The manner in which the locking is performed can be best understood from Figures 5 to 8, in which a single post and locking device is shown in both positions. Obviously, the action is repeated simultaneously at the other points of locking so that the description of one will suffice for all.

Let it be first assumed that the free ends of the posts are released for the purpose of removing or adding sheets to the contents 4, (Figures 5 and 6) so that the posts are in unlocking or released position, in which the sleeve 15 is shifted to the right extremity of its movement, wherein the notch 18 registers with the notch 14 of the tubular or internal rail 12, and the larger 130

notches 17 are shifted to the right of and out of register therewith. So also the locking pins are withdrawn from the notches 12, leaving a free space for the entrance 5 of the post end. Thus, when the top cover 1, is positioned so that the notch 18 opens toward the post, its end may be inserted through the opening formed thereby and is guided into position to be engaged by the 10 locking pin, which stands in readiness to be thrust laterally through the eye in the post end.

With the post thus positioned, the sleeve is shifted to the left by pressing against 15 its right end, to the positions shown in Figures 7 and 8. Now the notch 18 is carried beyond and to the left side of the recess 12 of the rail, and the notch 17 into register therewith, the pin 19, guided in the tubular 20 rail, being at the same time thrust through the eye in the end of the post and the locking is completed, whereupon the pin becomes a hinge pin on which the post may turn.

25 In this connection it is to be observed that the posts are hinged at both ends, and the recesses in the tubular members are cut away or extended circumferentially, so that posts can swing with comparative freedom 30 about their axis. In this manner the binder acquires considerable flexibility, and in this respect is not unlike a permanently bound book. It is also to be observed that the notches 18 serve primarily as guides for 35 the ends of the posts so that it is only necessary to insert the post ends into the opening formed thereby, and they are automatically positioned for locking. Moreover, the locking pins in locking position 40 are supported on either side of the post by the tubular rail, so that a perfect hinge is formed without danger of the pins being bent and their operation rendered faulty.

The advantage of the construction herein 45 disclosed resides in a simplicity and lightness of construction, that permits of a wide application to loose leaf devices, with marked advantages over the ordinary ring binders and others that depend on tension 50 to hold the posts in locked position, in that it requires a positive action of the posts to effect the operation and when once locked it is quite impossible for the contents to be accidentally released. In short, the binder 55 in locked position is practically as secure as a permanent binder or bound volume.

Having disclosed a preferred embodiment of the invention, I claim:

1. In a loose leaf binder the combination 60 of a cover, a post extending transversely of said cover and secured thereto at one end, and means for locking the other end of said post, comprising a fixed tubular member secured to the cover and provided 65 with a recess to receive the end of said post,

a slideable member mounted on said fixed member and having an opening adapted to register with the recess of said fixed member to guide the end of said post into position for locking and a locking member 70 fixed to said slideable member and shiftable into and out of locking engagement with said post.

2. In a loose leaf binder the combination 75 of a cover, a binding post extending transversely of said cover, and secured at one end thereto, a tubular member secured to said cover and provided with a notch to receive the end of said post, a sleeve mounted on said tubular member and 80 adapted for limited endwise sliding movement thereon, said sleeve having an opening adapted to register with said notch to guide said post therein when said sleeve is shifted into one position and a locking member fixed to said sleeve and shiftable axially of said tubular member into and out of locking position with said post.

3. In a loose leaf binder, the combination 90 of a cover, a binding post extending transversely of said cover and means for locking an end of said post to said cover, comprising a tubular rail secured to said cover, a portion thereof being removed to provide a recess for the end of said post, a sleeve 95 mounted on said rail for limited endwise movement thereon, said sleeve having a recess adapted to register with the recess of said rail in one position thereof and an opening adapted to admit the end of said 100 post and to register with said notch in another position thereof, and a locking member fixed to said sleeve and shiftable therewith into and out of locking engagement 105 with said post.

4. In a loose leaf binder the combination 110 of a cover, a binding post secured at one end to said cover and means for detachably securing the other end thereto comprising a tubular rail secured to said cover and having a portion removed to provide a notch to receive the end of said post, a sleeve slideable on said tubular rail and having an opening 115 therein adapted to guide said post into the notch of said rail, and a locking member movable with said sleeve to engage the end of said post, said opening and locking member being relatively positioned, to effect the shifting of said opening out of register with said notch as said locking member is carried into locking engagement with said post.

5. In a loose leaf binder, the combination 120 of a cover, a binding post secured at one end to said cover and means for detachably securing the other end thereto comprising a tubular rail secured to said cover and having a portion removed to provide a recess for the end portion of said post, a sleeve 125 slideable on said tubular rail and having a complementary recess and a notch opening 130

into said recess and adapted to guide the end of said post into locking position and a locking member movable with said sleeve and axially of said tubular rail to engage said post.

6. In a loose leaf binder the combination of a binder cover, a post secured at one end to extend transversely of said cover, a tubular rail having a notch to receive the free end of said post, a sleeve surrounding said rail and provided with an opening to admit the end of said post, a locking pin fixed to said sleeve, said sleeve being slideable through a limited distance in opposite directions, whereby said opening is shifted into and out of register with the notch of said rail and said locking pin is simultaneously shifted out and into locking position across said notch.
- 10 7. In a loose leaf binder the combination of a binder cover, a post secured at one end to extend transversely of said cover, a tubular rail having a recess to receive the free end of said post, a sleeve surrounding said rail and having a limited sliding movement thereon, said sleeve having an opening adapted in one position of the sleeve to register with the recess in said rail, and a locking pin secured to said sleeve and shiftable therewith axially of said tubular rail to engage and release the end of said post.
- 15 8. A loose leaf binder comprising a binder cover, a post hinged at one end to extend

transversely of said cover, a tubular rail having a recess to receive the free end of said post, a sleeve mounted on said rail and provided with a recess adapted to register with the complementary recess in said rail, in locking position and a notched opening into said recess and adapted to register with the recess in said rail in unlocking position, and a locking pin mounted within said sleeve and movable axially within said rail transversely of the recess thereof to engage and release said post.

9. In a loose leaf binder the combination of a cover, posts hinged at one end to said cover and adapted for locking connection at their other ends, and locking means comprising a tubular rail, having portions removed to form notches to receive the ends of said posts, a sleeve surrounding said rail and having portions removed to form complementary notches adapted to register with the notches of said rail in one position and an opening offset laterally from the notches of said sleeve and adapted to form openings to receive the ends of said posts in another position of said sleeve and locking pins fixed to said sleeve and movable transversely of the notches of said rail, to lock and release said posts.

In witness whereof, I hereunto subscribe my name this 23rd day of January, A. D., 1924.

JOSEPH KAHN:
